UNITED STATES PATENT OFFICE.

GRENVILLE MELLEN, OF WEST ORANGE, NEW JERSEY, ASSIGNOR TO CONTINUOUS CASTING CORPORATION, OF NEWARK, NEW JERSEY, A CORPORATION OF VIRGINIA.

CONTINUOUS CASTING-MACHINE.

1,321,658.

Specification of Letters Patent. Patented Nov. 11, 1919.

Application filed June 17, 1915. Serial No. 34,735.

To all whom it may concern:

Be it known that I, GRENVILLE MELLEN, a citizen of the United States, residing at Llewellyn Park, West Orange, in the county 5 of Essex and State of New Jersey, have invented certain new and useful Improvements in Continuous Casting-Machines, of which the following is a specification.

My invention relates to improvements in 10 machines for casting continuously rods or bars of any desired length and has for its object to simplify the construction of such machines. My machine is of that type in which the molten metal is cast into a mold 15 cavity formed between series or chains of coöperating moving mold-sections; and of that particular type in which the chains of mold-sections are moved vertically, or in a substantially vertical direction. One feature 20 of my improvement consists in omitting altogether the sprocket or other chain-guiding wheels at the lower end of the machine, thereby avoiding all difficulties of adjustment by allowing the mold-chain to swing 25 free. Further objects of the invention relate to means for cooling the mold-sections; to means for cleaning and lubricating the mold-sections; and to an improved means for introducing the metal into the mold 30 cavity and controlling its level therein.

Referring to the drawings,—

Figure 1 is a side elevation of the machine;

Fig. 2 is a plan or top view of Fig. 1;

Fig. 3 is an elevation of the machine, parts 35 being cut away;

Fig. 4 is a sectional elevation of the casting tube and accompanying parts;

Figs. 5 and 6 are detail views of the 40 device for holding the tube in place;

Fig. 7 is a section of the lubricating apparatus; and

Fig. 8 is a cross-section through the mold-chain.

Referring to the drawings, A is a structural steel frame supporting at its upper end sprocket-wheel 1 mounted in shaft 2 and sprocket-wheel 3 mounted in shaft 4. Passing over these sprockets are mold-chains 5, 6, consisting of a series of mold-blocks linked together, and preferably constructed and operated as shown in my Patent No. 1,139,885, patented May 18, 1915. The mold-blocks of chain 6 move over a fixed 55 guide 7. Bearing against the backs of the

molds of chain 5 is a plate 8 or a series of such plates, held inwardly by a series of springs. The mold-chains are thus held in transverse metal-sealing engagement, the springs being strong enough to produce so much friction between the backs of the mold-blocks and the guides that the molds will not move except as they are pushed downward by the power-driven sprockets, the ends of the mold-blocks thus being forced into endwise metal-sealing engagement. Suitable side-guides (not shown) may be provided of the type shown in my Patent No. 1,139,889, patented May 18, 1915. The mold-blocks, while in coöperative metal-sealing engagement are thus pushed downward until they emerge from between the guides. Instead of passing the mold-chains around sprockets or guide-wheels at the lower end of the machine the lower bights of the mold-chains are allowed to swing unguided and are then led upward over inclined fixed guides 10, 10, back to the sprockets of the top of the machine. As they pass upward along these guides 10, 10, they are sprayed by jets 11 of cooling water, the jets being connected to a valve-controlled supply-pipe 12. Revolving brushes 13, 13 driven by suitable gearing from shaft 2 are arranged to clean the inner surfaces of the mold-blocks, and a suitable dressing, such as castor or lard oil, is applied to the mold-sections by means of an "air-brush" device 14. The backs and sides of the blocks where they bear against the guides are lubricated with a heavy graphite grease from the cup 15, whence the grease is delivered by gear pump 16 (driven from one of the main shafts) and distributor 17 to the various surfaces. 18 is a receiving crucible which receives the molten metal from the crucible in which it is melted, 19 being a rest for the melting crucible during the pouring. 20 is a valve for controlling the flow of molten metal from crucible 18, 100 this valve being in turn controlled by a solenoid 21 included in circuit with the battery 22, wire 23, the molten-metal and frame of the machine and wire 24.

The manner in which the solenoid operates the valve 20 will be apparent from Figs. 1, 2, and 4, and is fully described in my Patent No. 1,139,888, patented May 18, 1915. 40 41 is a driving shaft connected to any suitable variable-speed motor. 41 is a bevel gear 110

box, and 42 a second shaft which, by means of a worm and worm-gears, drives the sprocket-wheels 1 and 3.

43, 43, are a series of water-cooled boxes 5 for cooling the mold-sections, and may be arranged in the manner shown in my Patent No. 1,139,885, patented May 18, 1915.

Referring to Fig. 4, 26 is a graphite distance piece having an opening therethrough, 10 and, surrounding its lower portion, is a sleeve 27, cut away at one side to permit passage of wire 23 and its coating of plastic insulation, 28, which may be made of asbestos and fire-clay. 29 and 33 are binding 15 wires for securing the wire 23 to the silica pouring-tube 30, which abuts against the distance piece 26. 31 are mica washers interposed between the upper end of the tube and the sleeve 27, the tube being secured in 20 the sleeve by set screws 32. Additional insulation 34 is provided to insulate wire 23 from the tube 30. 35 is a finely-tapered pointed graphite tip secured to the end of wire 23 by a threaded brass connection, and 25 extending as shown below the end of the silica tube.

I have found that it is important to provide a finely-tapered and pointed graphite tip for this electrical connection, as by this 30 construction the best results, as far as the avoidance of short-circuiting accretions of soot and zinc-oxid (when brass is being cast), are obtained.

In operation, the molten metal flows out 35 of the crucible through the silica casting tube 30 into the mold cavity formed between the series of co-operating mold-blocks, its level in the mold cavity being automatically controlled by the solenoid in a manner to 40 be later described. As the mold-sections move downward, the metal chills and solidifies and is delivered at the bottom in the form of a bar or rod.

Before the mold-sections are again used, 45 it is important that they be thoroughly cooled, cleaned and provided with a facing of suitable material to prevent sticking of the metal. For these purposes they are subjected on their upward journey to the action 50 of a series of water-sprays or jets, the quantity of liquid being so regulated that all the liquid projected against the heated mold-sections is evaporated, leaving the mold-sections dry. In their further upward movement they pass underneath a rotating brush 55 13, which removes any scale or other adhering foreign particles, and are then sprayed by means of an "air-brush" 14 with a suitable facing material, such as castor oil or 60 lard oil.

This facing of oil, preferably castor oil, when volatilized by contact with the hot metal, leaves a slight deposit on the mold 65 which prevents the metal sticking thereto and at the same time produces but a very

small amount of smoke which is deleterious as the resulting carbon forms conducting paths for short circuits of the regulating apparatus. In Fig. 7 is shown in detail the means for lubricating the backs and sides 70 of the blocks with heavy grease in order to lessen the friction between the blocks and guides. The grease cup 15 is provided with a plunger 50, by which grease is delivered to the gear-pump 16 which may be driven 75 from the main shaft. The grease delivered by the pump 16 to the distributor chamber 17 is conveyed by pipes 51, 51 to the sides of the blocks and by pipes 52, 52, to the backs of the blocks, as shown in Fig. 8, the 80 pipes being connected to suitable passages in the guides N, N', and 73, 74. These guides may be of the construction and arrangement shown in my Patent 1,139,889, patented May 18, 1915. As shown in Fig. 3, the grease 85 is applied to the mold-blocks through pipes 52 after they have been filled with molten metal, as it is important to insure that the mold-blocks are tightly pressed together before the grease is applied, so that no grease 90 shall get within the molds. If grease is allowed to come into contact with the molten metal, explosions are liable to occur. 53, 53 are adjusting screws to control the grease 95 supply.

The automatic control of the level of the molten metal in the mold is effected by means of the solenoid 21. If the metal rises too high, a circuit is closed, this circuit being closed through wire 23, battery 22, 10 solenoid 21, wire 24, the frame of the machine, and the molten metal. The solenoid thereupon operates to close or partly close valve 20 and cut off or lessen the supply of metal. The level of the molten metal thereupon falls and breaks contact with tip 35, the solenoid is deenergized and by the action of the spring 40, the valve 20 is again opened. The automatic solenoid control thus takes care of any irregularities in feed, 11 the rate of travel of the mold-sections being so regulated by control of the driving mechanism as to maintain under normal conditions the level of the metal at the point desired.

It will be noted that the lower bights of the chains of mold-sections are allowed to sag freely at their lower ends, thus permitting the free expansion and contraction of the chains.

As shown in Figs. 1 and 2, the machine as a whole is mounted to one side of the center of the structural steel frame-work. This arrangement enables the machine to be uncoupled along its center line and one side 1 pushed away from the other so as to separate the molding-chains for the purpose of cleaning out the same, in case of necessity.

I claim:

1. A casting machine comprising endless 1

- chains of coöperative mold-blocks, power-driven wheels, located at the upper portion of the machine, over which the chains pass, and means for holding the mold-blocks in metal-sealing engagement during their downward movement, the lower bights of the chains being free.
2. A casting machine comprising endless chains of coöperative mold-blocks, power-driven wheels, located at the upper portion of the machine, over which the chains pass, means for holding the mold-blocks in metal-sealing engagement during their downward movement, the lower bights of the chains being free, and means for cooling each of the chains during its return movement.
3. A casting machine comprising endless chains of coöperative mold-blocks, power-driven wheels, located at the upper portion of the machine, over which the chains pass, means for holding the mold-blocks in metal-sealing engagement during their downward movement, the lower bights of the chains being free, and means for cooling, means for brushing, and means for supplying a facing material to each of the chains during its return movement.
4. A casting machine comprising endless chains of coöperative mold-blocks, power-driven wheels, located at the upper portion of the machine, over which the chains pass, means for holding the mold-blocks in metal-sealing engagement during their downward movement, the lower bights of the chains being free, and means for spraying a cooling fluid on each of the chains during its return movement.
5. A casting machine comprising endless chains of coöperative mold-blocks, means for maintaining the mold-blocks in metal-sealing engagement during their forward casting movement, means comprising water spraying devices for cooling the water-blocks during their return movement, and means for guiding the chains on such return movement.
6. A casting machine comprising endless chains of coöperative mold-blocks, means for maintaining the mold-blocks in metal-sealing engagement during their forward casting movement and a forced feed means for applying grease to the outside of said blocks.
7. A casting machine comprising endless chains of coöperative mold-blocks, means for maintaining the mold-blocks in metal-sealing engagement during their forward

casting movement and a forced feed means for applying grease to the backs of said blocks.

8. A casting machine comprising endless chains of coöperative mold-blocks, means for maintaining the mold-blocks in metal-sealing engagement during their forward casting movement and a forced feed means for applying grease to the backs and sides of said blocks.

9. A casting machine comprising endless chains of coöperative mold-blocks, means for maintaining the mold-blocks in metal-sealing engagement during their forward casting movement and a forced feed means for applying grease to the outside of said blocks comprising a grease supply, a pump and conduits leading therefrom to the outside of said blocks.

10. A casting machine comprising a sectional mold, means for opening and closing the mold members while traveling progressively to receive molten material and to discharge the casting, means for discharging cooling fluid separately upon each of the mold members after the latter operation, and means in the further progress of the mold members for directing fluid upon each of the mold members to prevent sticking of molten metal thereto.

11. A casting machine comprising endless chains of coöperative mold-blocks, power-driven wheels, located at the upper portion of the machine, over which the chains pass, means for holding the mold-blocks in metal-sealing engagement during their downward movement, the lower bights of the chains being free, and means for guiding the chains on their upward movement.

12. A casting machine comprising endless chains of coöperative mold-blocks, separable power-driven wheels, located at the upper portion of the machine, over which the chains pass, means for holding the mold-blocks in metal-sealing engagement during their downward movement, the lower bights of the chains being free, and a support for the upper portion of the machine of greater width than said portion, whereby the machine can be uncoupled along its center line.

In testimony whereof I affix my signature in presence of two witnesses.

GRENVILLE MELLEN.
